UNITED STATES PATENT OFFICE

114,405

DESIGN FOR AN APRON

Cora May Mitchell, Rock River, Wyo.

Application October 18, 1938, Serial No. 80,523

Term of patent 3½ years

To all whom it may concern:

Be it known that I, Cora May Mitchell, a citizen of the United States, residing in Rock River, in the county of Albany, State of Wyoming, have invented a new, original, and ornamental Design for an Apron, of which the following is a specification, reference being had to the accompanying drawing, forming a part thereof.

I claim:

The ornamental design for an apron, as shown.

CORA MAY MITCHELL.
